UNITED STATES PATENT OFFICE.

JOHN RAPHAEL ROGERS, OF BROOKLYN, NEW YORK, ASSIGNOR TO MERGENTHALER LINOTYPE COMPANY, A CORPORATION OF NEW YORK.

TYPOGRAPHICAL COMPOSING-MACHINE.

1,071,582.

Specification of Letters Patent. Patented Aug. 26, 1913.

Application filed February 1, 1912. Serial No. 674,662.

To all whom it may concern:

Be it known that I, JOHN RAPHAEL ROGERS, a citizen of the United States, and a resident of Brooklyn, county of Kings, and 5 State of New York, have invented a new and useful Improvement in Typographical Composing-Machines, of which the following is a specification.

My invention relates to typographical 10 composing machines, such as linotype machines of the general organization represented in Letters Patent of the United States, No. 436,532, to O. Mergenthaler, wherein circulating matrices are released 15 from a magazine in the order in which their characters are to appear in print and then assembled in line, together with expanding spacers, the composed line transferred to the face of a mold, the mold filled with molten metal to form a slug or linotype against the matrices which produce the type characters thereon, and the matrices thereafter elevated and returned through a distributing mechanism to the magazine or magazines 20 from which they started.

More particularly the invention relates to that class of typographical machines in which are employed type or matrices provided with two or more characters, and devices by which the position of the type or matrices may be varied so that each will present one or another of its characters in the line, as demanded. Such an arrangement is disclosed in my U. S. Letters Patent, No. 615,909, although the present construction differs therefrom in various particulars which will subsequently be set forth more fully. For instance, when plural-character type or matrices have been assembled at different levels, it is customary to restore them to the same level before distribution, and in the said Letters Patent this leveling operation is effected by the employment of a retractable ledge or support in the casting or first elevator. In the form herein illustrated and described the supporting ledges in the first elevator are fixed and permanent, and therefore the leveling occurs at a subsequent point in the cycle of operations, namely, in the upper transfer channel, while the type or matrices pass from the first elevator into engagement with the second elevator.

In order to effect this result, I mount between the first elevator and second elevator

leveling means comprising an inclined blade which engages the type or matrices in their passage from one elevator to the other, and whereby they are brought to a common level in line with the supporting devices on the 60 second elevator. In the specific form illustrated and described, the inclined blade is located in position to engage the matrices centrally thereof, and preferably at the bottom of the distributing notches so that they 65 are moved downward thereby in their passage. The supporting means for this blade are preferably connected to the spacer depressor bar and project laterally toward and into a corresponding notch formed in the 70 second elevator. This special arrangement subserves the function of centering the second elevator in proper position and of registering the bar thereon centrally with reference to the inclined blade, so that the 75 matrices are not only lowered by the latter but are also accurately brought thereby into proper position to engage the bar.

My invention is illustrated in the accompanying drawing in preferred form by way 80 of example and as applied to a linotype machine, but obviously many changes and variations may be made therein and in its mode of application without departure from the scope of the invention; and generally speaking I desire it to be understood that I do not limit myself to any specific form or embodiment except in so far as such limitations are specified in the claims.

Referring to the drawing: Figure 1 is a 90 longitudinal vertical section, partly broken away, through the upper transfer channel, showing the first and second elevators in operative relation thereto; Fig. 2 is a top plan view thereof; Fig. 3 is a transverse vertical 95 section through the first elevator, taken substantially on the line 3—3 in Fig. 1; Fig. 4 is a transverse vertical section through the channel and second elevator, taken substantially on the line 4—4 in Fig. 1; and Fig. 5 100 is a detached detail view illustrating the operative engagement of the leveling means with the second elevator.

Figs. 1 and 2 illustrate the relations of the parts, after the first elevator A has 105 come to its uppermost position and brought the upper ends of the spacers Y into contact with the spacer depressor bar B, and the second elevator D has descended into the upper transfer channel C, at which time 110

the line of matrices X and spacers Y is moved by the customary transfer slide or pusher E from the first elevator A into the channel C . During this operation, the spacers Y are separated from the line in the ordinary manner, and as this feature does not relate to my present invention, it requires no further description herein. The parts and operations so far described are all well known in the art and are substantially similar to those set forth in the previously mentioned patent to Mergenthaler and as applied in the commercial linotype machine.

As will be noted from Fig. 3, the first elevator A is provided with fixed ledges A^1 which engage under the upper ears of the matrices X in their lower position, and with a fixed ledge A^2 which engages beneath the body of the matrices to sustain them in their upper position. Due to the permanent character of the ledge A^2 , the matrices supported thereby cannot be lowered within the elevator, and they are brought subsequently to the level of the others, before they pass into engagement with the bar D^2 of the second elevator D , this being effected by the inclined blade B^2 which engages centrally in the notch X^1 of the matrices as the latter are moved into the channel C , by which operation the upper and lower matrices are brought to a common level upon the ledge C^1 in the transfer channel.

One of the principal features of my invention is the arrangement and location of the leveling means, comprising the blade B^2 and its support B^1 . I preferably form the depressor bar B with the lug or portion B^1 , projecting into the channel C and into the path of the second elevator D , which latter is formed with a correspondingly shaped and located recess D^1 to engage the projecting lug, when the elevator is in operative relation to the channel. The inclined blade B^2 is connected to the bottom of the projection or lug B^1 and is so located that it registers with the central line of the elevator bar D^2 when the latter is in operative position, as shown clearly in Fig. 5. This arrangement of the parts, and particularly due to the engagement of the lug B^1 in the notch D^1 of the elevator D , insures the correct location of the elevator and the proper registration of the blade B^2 with the bar D^2 , so that the matrices are thereby accurately guided onto the bar.

The operation of the devices will now be apparent: Referring to Figs. 1, 4 and 5, the matrices X are moved out of the first elevator A by the transfer device E , and thereby the central notches X^1 of the upper matrices are brought into engagement with the inclined blade B^2 , whereby they are lowered to the same level with the other

matrices on the channel ledge C^1 . In addition, the continued engagement of the blade B^2 in the notches X^1 of all the matrices brings them into accurate relation to the bar D^2 , so that the further action of the pusher device E properly transfers them thereto. The elevator D then conveys them in the ordinary manner to the distributing mechanism, not herein shown, but as set forth in the said Mergenthaler patent. 70 75

As previously stated, I have shown my invention in preferred form by way of example and obviously there will be many changes and variations therein and in their mode of application, which will suggest themselves to those skilled in the art and still be comprised within its spirit. 80

Having thus described my invention, its construction and mode of operation, what I claim and desire to secure by Letters Patent 85 of the United States is as follows:

1. In a typographical composing machine comprising notched type or matrices, the combination of a support provided with fixed means to sustain the type or matrices at different levels therein, means for removing the matrices therefrom, and an inclined blade located beyond said sustaining means to engage in said notches when the type or matrices are removed from the support in 90 order to bring them to a common level. 95

2. In a typographical composing machine comprising type or matrices, the combination of a support provided with fixed means to sustain them at different levels therein, 100 means for removing the matrices therefrom, and an inclined device located beyond the sustaining means to engage the central portions of the type or matrices as they are removed from the support in order to bring 105 them to a common level.

3. In a typographical composing machine, the combination of type or matrices, means to support them at different levels, an elevator to receive them from said supporting means, and means to level the type or matrices during their transfer, the said leveling means engaging the elevator to insure proper registration. 110

4. In a typographical composing machine, the combination of type or matrices, means to support them at different levels, means to receive them therefrom, and means to bring the type or matrices to a common level, the said receiving means being formed 115 120 with a recess to engage the said leveling means.

5. In a typographical composing machine, the combination of type or matrices, means to support them at different levels, an elevator-bar to receive them therefrom, and means to bring them to a common level during their transfer, the said leveling means comprising an inclined blade to engage and center the bar. 125 130

6. In a linotype machine comprising type or matrices, the combination of a support provided with fixed means to sustain them at different levels therein, means for removing the type or matrices therefrom, and a spacer depressor bar coöoperating therewith, the said depressor bar being provided with an inclined leveling blade located beyond said sustaining means to engage the type or 10 matrices during their removal.
7. In a typographical composing machine, the combination of type or matrices, a device provided with fixed means to support them at different levels, a movable elevator to receive them therefrom, and stationary leveling means engaging with the elevator, the said leveling means comprising an inclined blade.
8. In a typographical composing machine, 20 the combination of type or matrices, a device provided with fixed means to support them at different levels, a movable elevator to receive them therefrom, and stationary leveling means engaging with the elevator and comprising an inclined blade, and means for transferring the type or matrices from the said device along the blade onto the elevator.
9. In a linotype machine, the combination of the type or matrices, the first elevator
- provided with fixed means to support them at different levels, the second elevator to receive them therefrom, leveling means engaging the said second elevator and comprising an inclined blade, and means for transferring the matrices from the first elevator 30 along the blade onto the second elevator.
10. In a linotype machine, the combination of the second elevator D having the notch D¹ and the bar D², and the leveling means B¹ provided with the inclined blade 40 B², the leveling means B' being adapted to engage the notch D¹ to insure proper registration.
11. In a linotype machine, the combination of the second elevator D having the 45 notch D¹ and the bar D², and the spacer-depressor bar B having the extension B¹ and the inclined blade B², the leveling means B¹ being adapted to engage the notch D¹ to insure proper registration. 50

In testimony whereof I hereunto set my hand this twenty seventh day of January, 1912, in the presence of two attesting witnesses.

JOHN RAPHAEL ROGERS.
